SHUTTLE LOCK FOR LOOMS

James Chapman, Sr., and Roger Nixon
Reynolds, Sr., Atlanta, Ga.

Application October 13, 1950, Serial No. 190,034

5 Claims. (Cl. 139—187)

1

Our invention relates to shuttle locks for looms, and it is an object of the same to provide means for locking a shuttle in its box at the end of its stroke across the lay and to prevent rebounding of the shuttle, which means is controlled by the movement of the shuttle itself.

Other objects are to provide a shuttle locking means that is positive and certain in action and simple in construction, which is so durable that it will wear as long as other parts of the loom, and which will release the shuttle completely before the picker strikes it in a picking operation.

Referring to the annexed drawings, which are made a part of this application and in which similar reference characters indicate like parts:

Fig. 1 is a cross sectional view of so much of a loom as will illustrate a shuttle and parts cooperating therewith for the purposes of our invention, only one end of the lay and cooperating parts being shown and it being understood that certain parts are duplicated at the other side of the loom,

Fig. 2, a top plan of the same,

Fig. 3, a section lengthwise of the loom, on line 3—3 of Fig. 1,

Fig. 4, a view similar to Fig. 1, but showing the parts in another position,

Fig. 5, a plan of parts shown in Fig. 4.

Fig. 6, a longitudinal section on line 6—6 of Fig. 4, and

Fig. 7, a detail of parts shown in other figures.

In the drawings, reference character 20 indicates the crankshaft of a loom, which crankshaft is connected by a pitman 21 at each end of the loom to brackets 22 on the lay sole 23, that is supported on lay swords 24. A shuttle 25 moves in a race on the lay sole, from one to the other of two shuttle boxes at the ends of the lay, the shuttle being impelled by a picker stick 26 with a picker 27 at its upper end. The shuttle boxes comprise upstanding front members 28 and rear binders 29 that are moved by springs 30 and protection springs (not shown) about pivots 31 to arrest the shuttle and hold it in place in a box. All the parts so far described are of conventional character as commonly used in looms.

The device of our invention comprises a swivel stand 32 that is affixed to the lay by bolts 33, said stand carrying what we call a swivel 34 which is a lever of the first class and is mounted on a pivot 35 for oscillatory motion in a plane extending lengthwise of the loom, said lever 34 being biased toward the position shown in Fig. 6 by a spring 34'. A bunter 36 is secured to the

2

pitman 21 by a bolt or screw 37, said bunter comprising an arm extending alongside the pitman and preferably being adjustable along the pitman to vary the time at which it acts during the beat up of the lay. The swivel has a laterally extending finger 38 which extends into the path of movement of the inner end of the binder 29, so that it presses the binder toward the shuttle when free to act, the spring 34 serving as binder pressing means auxiliary to binder spring 30 and protection rod spring.

A latch 39 is formed on or attached to the righthand end of a rod 40 that is mounted to slide in a bore provided in a casting 41 secured to the lay, said rod being biased for endwise movement toward the swivel by means of a coil spring 42 encircling the rod and bearing at opposite ends against part 41 and an abutment 43 adjustably secured to the rod by a setscrew 44, said spring tending to move the parts into the position of Fig. 1, where the latch is positioned back of the swivel and prevents the swivel from being tilted by spring 34' toward the position for engagement of its arm 38 with the binder. Near the lefthand end of the rod 40 a block 46 is adjustably secured to the rod by a setscrew 47, said block carrying a pin 48 on which is mounted an abutment in the form of a roller 49 that lies in the path of the picker stick. The rod 40 is bent rearwardly to provide a part *a* lying underneath the lay, then upward to provide a vertical part *b*, then laterally to form an arm *c*, and a hook-like bend at its free end to bear against the front face of finger 38.

In the operation of our device, let it be assumed that the parts are in the position of Fig. 1, wherein the box at the right is empty, the shuttle moving toward the left as indicated by the arrow. The latches are held behind the swivels, by the action of springs 42, and therefore they hold the swivels away from the binders. The left hand picker stick is spaced somewhat from the limit of its leftward movement, and the box at the left is empty, to receive the approaching shuttle. When the shuttle now strikes the picker stick, or other movable part adapted to operate rod 40, the stick is moved to the left by the impact of the shuttle, as it goes home in the shuttle box, the stick contacting with roller 49 and pulling the rod 40 to the left against the action of spring 42 sufficiently to withdraw the latch from swivel 34 and so to release the swivel 34 as the shuttle reaches home position. As soon as the shuttle contacts with the binder it begins to be retarded, as usual, but

when swivel 34 is released by the latch, it snaps against the binder due to the action of spring 34' and locks the shuttle in home position with a positive and certain action. The swivel moves only a short distance, and the positions of parts in Figs. 6 and 7 are exaggerated to emphasize the movement of the swivel. When the shuttle is fully home it is under the tension of the binder spring, the spring on the protection rod (not shown), and the added tension of the spring of the swivel, whereas the box at the other end of the lay is empty and subject only to the tension of its binder spring.

As the crankshaft turns in the direction of the arrow in Figs. 3 and 6 it passes front center and approaches top center in preparation for the next pick to the left, and at about 15° before it reaches top center the bunter on the pitman rod engages the lower end of the swivel and moves it from the position of Fig. 6 toward that of Fig. 3 away from the binder. As the crankshaft reaches top center the shuttle is picked out of the loose box, the bunters now holding the swivels at both ends of the lay so as to remove tension of the binders from the boxes and both latches moving into position underneath their swivels.

As the crankshaft passes back center the bunters pass away from the swivels, but the latches hold them and so maintain the binders in idle position while the shuttle completes its travel on this pick. When the crankshaft reaches bottom center or nearly so the shuttle reaches home and pulls the latch from under the swivel by its engagement with the lefthand picker stick, and the springs 30 and 34' act on the corresponding picker to snap the binder into locking position.

It will be obvious to those skilled in the art that many changes may be made in the mechanisms herein disclosed and in their mode of operation, all without departing from the spirit of the invention; and therefore we do not limit ourselves to what is shown in the drawings and described in the specification, but only as indicated in the appended claims.

Having thus fully described our invention, what we claim is:

1. In a loom, a lay, a crankshaft, a pitman connecting the lay to the crankshaft, a shuttle box on the lay, a spring-pressed shuttle binder, and a picker stick, the combination therewith of a swivel stand on the lay, a lever on the stand, said lever being pivoted for movement in a plane extending lengthwise of the loom, a finger extending laterally from said lever into the path of movement of said binder, resilient means moving said lever to force said finger against the binder, a bunter on the pitman for moving said

lever into idle position, a latch for holding said lever in such idle position, and means actuated by a shuttle at the end of its flight for releasing said latch.

2. In a loom, a lay, a crankshaft, a pitman connecting the lay to the crankshaft, a shuttle box on the lay, a spring-pressed shuttle binder, and a picker stick, the combination therewith of a lever pivoted on the lay to swing on a horizontal axis, said lever having arms above and below said axis, resilient means biasing the lever to force its upper arm against the binder to augment the action of the binder on a shuttle, a bunter on the pitman for pressing against the lower arm of the lever to move its upper arm away from said binder, a latch, and means for moving the latch into the path of the upper arm during such action of the bunter.

3. A device as in claim 2, including a latch rod 20 slidable lengthwise of the lay into and out of the path of said upper arm, means biasing the latch toward a position for inhibiting the movement of said upper arm, and an abutment on said latch rod for engagement by the picker stick to withdraw said latch rod.

4. A device as in claim 2, including a latch rod 30 slidable on the lay, said rod having a portion lying on top of the lay, and movable into the path of said upper arm to inhibit the action of said arm on the binder, another part below the lay, and a connecting portion at the rear of the lay; and an abutment on the latch rod for engagement by the picker stick to withdraw the latch rod from the path of said upper arm.

5. In a loom, a lay, a crankshaft, a pitman connecting the lay to the crankshaft, a lever pivoted on the lay to swing in a plane extending lengthwise of the loom, arms on the lever extending upward and downward from its pivot, resilient means biasing the upper arm of the lever toward the binder, an abutment on the pitman for acting on the lower arm of the lever to move its upper arm away from the binder, a latch, and means for moving the latch into the path of said upper arm during such action of the bunter.
